Patented May 21, 1918.

30 Inventor
Carl Frederick Gromann
By his Attorney
Adèle Pomeroy

UNITED STATES PATENT OFFICE.

CARL FREDERICH GROMANN, OF NEW YORK, N. Y.

ILLUMINATING DEVICE FOR VEHICLES.

1,266,678.

Specification of Letters Patent. Patented May 21, 1918.

Application filed May 26, 1916. Serial No. 99,961.

To all whom it may concern:

Be it known that I, CARL FREDERICH GROMANN, a subject of the Empire of Germany, and resident of the borough of Manhattan, in the county of New York and State of New York, have invented certain new and useful improvements in Illuminating Devices for Vehicles, of which the following is a specification.

10 This invention relates to an illuminating device for vehicles, automobiles or the like. The organization of the invention is characterized by a casing with a parabolic reflecting surface, to reflect light rays in parallel directions. The casing is provided with a removable number or name plate. A translucent glass of the casing has connected thereto a colored glass for a danger signal. An oil lamp and an electric bulb are located 20 in the casing and means are provided to energize the bulb when the lamp is inadvertently extinguished.

In the drawings Figure 1 represents a top plan view of the invention with a portion thereof broken away and a partial section as on the line 1, 1 of Fig. 2; Fig. 2 shows a front view of Fig. 1 with a portion cut away; Fig. 3 is a right hand side view of Fig. 1; Fig. 4 shows an enlarged section as 30 on the line 4, 4 of Fig. 2; Fig. 5 shows an elevation of a portion of Fig. 1 and section on the line 5, 5 of Fig. 1; Fig. 6 represents a top plan view of Fig. 5; Fig. 7 shows a partial section of Fig. 1 on the line 7, 7; Fig. 8 represents an enlarged partial section of Fig. 2 on the line 8, 8, and Fig. 9 represents an enlarged detail of some of the elements shown in Fig. 1.

The invention is shown with the casing 20, having the bottom 21, top 22 and back parabolic wall 23. A door 25 is hinged to the front of the casing by means of the spring hinge 25. The said door has provided therefor the translucent glass 26. 45 The frame of the door has built therewith the segmental portion 27, and in the latter and in the lower corner of the said frame is located the colored glass sector 28. A frame 29 is detachably fastened to the frame 50 of the door 25 by means of bolts 30. A stenciled number or name plate 31, with the opening 32 and numbers 33 bears against the glasses 26 and 28 and is detachably held in position by means of the frame 29. A 55 lock 34 is provided to lock the door 30 to the casing 20. To the bottom 21 of the cas-

ing are secured a pair of keepers 36. For each keeper there is provided a plunger 37. A spring latch 38 for each keeper has one end fastened to the door 25.

In closing the door the spring latch 38 locks with its keeper 36, and to open the door the operator forces up the plungers 37 by which spring latch 38 is disengaged from its keeper.

To the outside face of the wall 23 is fastened a bracket 42 with the arms 43, and the foot 45. By means of the foot 45 the casing 20 can be bolted in proper position on a vehicle. On the bottom 21 of the 70 casing are fastened a pair of guides 46 in which is engaged the bottom plate 47 of the lamp 50. A spring 51 fastened to the bottom 21 bears up against the plate 47 to clamp the lamp in position. A stop 52 75 and a spring 53 are also provided for the lamp to hold it in position. In the casing 20 and projecting from the back 23 is shown the electric lamp or bulb 55. A light shade or hood 58 is fastened to the bottom 21 of 80 the casing 20.

A selenium cell 60 with the binding posts 61, 62 is fastened to the hood 58. The said cell is protected from the light rays of the bulb 55 by the hood 58 and is exposed to the 85 light from the lamp 50. An electromagnet 65 with the foot 66 is fastened to the bracket 42. The magnet has the armature 67 which is pivoted on the post 68. A spring 69 has one end fastened to said armature and the other end thereof is fastened to the foot 66. A contact post 70 is supported on a bracket 71 extending from the bracket 42. The armature 67 and post 70 constitute an 90 electric switch.

95 Wires 72, 73 for electric current respectively connect the binding posts 61, 62 of the selenium cell and the magnet 65. An electric battery 74 is connected to the wire 73. A wire 75 connects the armature 67 and an 100 electric switch 76. A wire 77 connects the bulb 55 with the contact post 70. A second wire 78 connects the bulb 55, with the battery 80. The electric battery 80 is in series with the electric bulb circuit. 105 An electric bell 81 is shunted with the bulb circuit. The wire 82 connects the bell 81 and the contact post 70. The wire 83 connects the adjustable resistance 84 and the battery 80. Current flows from the battery 80 110 through the switch 76, wire 75, the armature 67, the contact post 70, the wire 82, the bell

81, the adjustable resistance 84, the wire 83 and back to the battery 80.

- To use the invention the lamp 50 is lighted to illuminate the numbers 33 on the stenciled number plate. When the lamp 50 is burning the effect of the light renders the selenium cell 60 conductive to electric current, and the electromagnet 65 is energized. This draws the armature 66 into contact with the said magnet against the tension of the spring 69, and no current is flowing through the circuit of the electric bulb 55. When the lamp 50 is extinguished, the selenium cell becomes a non-conductor of electric current and de-energizes the electro-magnet 65, which releases the armature 67, and the latter in turn makes contact with the contact post 70. This closes the electric bulb circuit, and the bulb is lighted and the bell 81 is caused to ring.
- If while the bulb 55 is lighted the bulb filament should break, the bell 81 would continue to ring because the bell circuit is still complete. When neither the lamp nor the bulb are in use the switch 76 should be open. The switch 76 should be closed only after the lamp 50 is lighted.

The invention may however be used without the bell 81, by eliminating the wires 82 and 83.

- The number plate 31 can be easily detached for another number plate. The colored glass sector 28 is always in view when either of the lights in the casing are operative.

Having described my invention what I desire to secure by Letters Patent and claim is:

1. In a device of the character described

the combination, of a casing, an electric lamp in the casing, a light shade under the electric lamp, a selenium cell under the light shade, a fuel lamp in the casing in front of the light shade, an electric circuit for the said cell and an electric circuit for the lamp, the cell with its circuit energizing the electric lamp when the non-electric lamp is ex-
tinguished.

2. In a device of the character described the combination of a casing, an oil lamp in the casing, an electric bulb in the casing, a selenium cell in the casing, a shade for the selenium cell positioned to screen it from the light of the electric bulb, an electromagnet operated by said selenium cell and a switch operated by the electromagnet to light the said bulb.

3. In a device of the character described the combination of a casing, an oil lamp in the casing, an electric bulb in the casing, a selenium cell in the casing, a shade for the selenium cell positioned to screen it from the light of the electric bulb, an electric magnet operated by said selenium cell, a switch operated by the electromagnet to light the bulb, a source of electric current for the electric bulb and an electric bell in circuit with said source of electric current and said switch.

Signed at the borough of Manhattan, in the county of New York and State of New York, this 8th day of May, A. D. 1916.

CARL FREDERICH GROMANN.
